INVENTOR.

THOMAS DICKINSON, JR., OF BUFFALO, NEW YORK, ASSIGNOR TO
HIMSELF AND THOMAS DICKINSON, OF SAME PLACE.

Letters Patent No. 87,551, dated March 9, 1869.

REvolvING FRAME FOR SHOWING GOODS.

The Schedule referred to in these Letters Patent and making part of the same.

To all whom it may concern:

Be it known that I, THOMAS DICKINSON, Jr., of the city of Buffalo, county of Erie, and State of New York, assignor to myself and THOMAS DICKINSON, of the same place, have invented a certain new and improved Revolving Frame for Show-Goods; and I do hereby declare that the following is a full, clear, and exact description thereof, reference being had to the accompanying drawings, making a part of this specification, and which represents a vertical section of my improved frame.

The nature of this invention consists in the construction, operation, and application of a frame, composed of a number of radial arms, or rods, upon a horizontal shaft, which shaft is revolved by clock-work, or any other suitable or convenient mechanical power, and the attachment, to any point upon said radial arms, of any kind of show-goods, such as jewelry, millinery, furnishing and dry goods, boots and shoes, photographs, confectionery, and the like, by means of suspended trays, hooks, clamps, springs, or other equivalent devices, in such manner that said show-goods will be revolved around the horizontal shaft, and thereby rendered more conspicuous and attractive in a show-window or other place of exhibition.

In the accompanying drawing, I have represented a frame, consisting of the horizontal shaft A and two sets of radial arms, B, four arms to each set; but the number of the arms, or their arrangement upon the horizontal shaft, may be varied according to the size of the apparatus, and the quality, size, and heft of the goods to be supported thereon.

C represents trays, or plates, which are suspended, by means of the rods c', between the two sets of arms, in such manner, that as the arms revolve around the shaft A, the trays will maintain their horizontal position. These trays are the most convenient devices for supporting show-goods, and suspending them upon the revolving arms. They are especially adapted for jewelry, samples of teas, coffees, and spices, ladies' boots

and shoes, varieties and fancy articles, confectionery and like goods, which may be displayed upon these revolving trays to great advantage.

For photograph-galleries, the trays may be dispensed with, the photographs or other pictures on exhibition being attached to both sides of a vertical plate, or frame, which is suspended perpendicularly between the two sets of arms, in a manner similar to the trays, as shown at D, or only one set of arms may be used, and the pictures suspended, singly or in pairs, in the manner shown at D', facing the side of the apparatus.

Dry goods, gents' furnishing-goods, and other like articles may be suspended from and arranged upon the radial arms B in still a different manner, and by means of other devices, according to the nature and size of the articles to be exhibited.

The horizontal shaft A is revolved slowly by suitable clock-work or other convenient mechanical power, thereby rendering the revolving frame, with the show-goods displayed thereon, a point of attraction, and more conspicuous than if these same goods were placed upon shelves in a common manner.

I am well aware that the construction of a revolving frame or reel, similar to the one herein described, is not new, being used in the shape of the so-called Russian swing, in the manufacture of patent bread, and for other purposes, and I do not, therefore, claim this construction broadly; but

What I claim as my invention, and desire to secure by Letters Patent, is—

A revolving frame for show-goods, as a new article of manufacture, consisting of the horizontal shaft A and radial arms B, the same being constructed and operating in the manner herein described, and for the purposes set forth.

THOMAS DICKINSON, JR.
